(57) **CLAIM**

The ornamental design for a bulldog stationery tab, as shown and described.

DESCRIPTION

FIG. 1 is a front view of the bulldog stationery tab in accordance with my new design,

FIG. 2 is a rear view of the bulldog stationery tab shown in FIG. 1;

FIG. 3 is a perspective view of the bulldog stationery tab shown in FIG. 1;

FIG. 4 is a left side view of the bulldog stationery tab shown in FIG. 1;

FIG. 5 is a right side view of the bulldog stationery tab shown in FIG. 1;

FIG. 6 is a top view of the bulldog stationery tab shown in FIG. 1; and,

FIG. 7 is a bottom view of the bulldog stationery tab shown in FIG. 1.

The long and short broken lines around the inside edge of the bulldog stationery tab define the bounds of the claimed design and form no part thereof.

The evenly spaced broken lines showing the clip and apertures in the middle of the bulldog stationery tab are included to show features that form no part of the claimed design.
